UNITED STATES PATENT OFFICE.

JOHN GARDNER, OF BOLTON-LE-SANDS, CARNFORTH, ENGLAND.

ELECTRIC SIGNALING CONTROLLED BY MECHANICAL VIBRATIONS.

Application filed March 17, 1920, Serial No. 366,561, and in Great Britain March 22, 1919.

This invention relates to that class of signaling apparatus in which an electromagnetic device, such as, e. g. a relay, and one or more transmitters or current-reducing devices more or less remote from the receiver, are in a normally closed circuit, an increase of resistance in a transmitter or current-reducing device brought about by mechanical vibrations, such as e. g. those caused in the 10 track by the passage of a railway train, so reducing the current in the circuit as to permit the release of an armature or the like, which, by its movement, closes a local circuit and effects the operation of a signaling device therein, the transmitter or current-reducing device being in effect a switch which is opened by the vibrations and closed by their cessation.

The main object of the invention is to 20 provide for the giving of a prolonged or continuous signal, even though the transmitter or current-reducing device may have become quiescent and the current flowing through the circuit of the relay or like device been 25 restored to the normal, until the signal is interrupted manually or automatically. Further objects of the invention are to provide for the testing of the apparatus at the signal receiving station and to improve 30 the details and arrangement of the apparatus.

According to the invention, I provide that on the armature or the like being released to close the local circuit and effect the operation of the signaling device therein, a second circuit is also closed whereby the return of the armature to normal position to open the local circuit is retarded or damped, or is positively delayed until permitted by the 40 opening of the second circuit by manual operation, or by automatically-operated means at a determined interval, so that a prolonged or continuous signal is given notwithstanding that the transmitter or current-reducing device may have become quiescent or normal.

The invention is hereinafter more fully described with reference to the accompanying drawings wherein Figs. 1 and 2 are diagrams illustrating two ways of carrying it into effect for signaling in connection with railways. Fig. 3 is a diagram illustrating how the several necessary appliances may be grouped to form a complete portable receiver, and Fig. 4 is a plan with the cover removed, and Fig. 5 a transverse section of

an improved arrangement of box for a portable transmitter or current-reducing device.

Referring to the drawings, *a* is a relay in the circuit of a battery *b*, and *c* is a microphonic transmitter in series with the relay *a* and mounted preferably on a sleeper at a suitable situation in the track, and which is operated by the mechanical vibrations caused by trains passing thereover, to reduce the 65 line current through the relay *a*. *d* is a bell in a local circuit which is normally open, as shown, and is closed on the de-energizing of the relay *a* by the armature *a*¹ thereof then contacting with a contact *e*. From 70 the contact *e* a lead *f* goes to a switch member *g* which normally contacts with a contact *h* in the circuit of the relay, the lead *f* and switch member *g* constituting a shunt 75 circuit from the relay circuit. On the de-energizing of the relay *a* and the release of its armature *a*¹ to close the bell circuit, the armature also completes the shunt circuit which so reduces the current flowing through the relay coil as to prevent the return of the armature to its normal position, notwithstanding that the distant transmitter *c* may have become quiescent, until the shunt circuit is broken. The shunt circuit is broken to allow of the return of the relay armature 80 and the stopping of the signal, by the operation of the switch member *g* by the manual depression of a stop key *j*. When it is not desired that the prolonged signal should be given the stop key *j* may be locked by a 85 detent in the depressed position to hold the switch *g* open.

Preferably, and as illustrated in Fig. 2, I provide, for opening the shunt circuit, a second or stop relay *k* through the armature *k*¹ of which the shunt circuit (comprising the leads *f*, *f*¹, armature *k*¹, contact *e*¹ and lead *f*¹) is normally closed, and the winding of which is in circuit with a second or stop transmitter *m* located at a suitable distance 90 beyond the first or starting transmitter *c*. With this arrangement, which is particularly suitable for giving signals at level crossings, on a train reaching the first or starting transmitter *c* the latter will be disturbed and the starting relay *a* de-energized to release its armature *a*¹ which then completes the circuit of the bell *d*, and also the shunt circuit, and the bell will continue to ring, notwithstanding that the starting transmitter *c* may 95 have become quiescent, until the train reaches the second or stop transmitter *m* and 100

disturbs same. On the disturbance of the stop transmitter m the stop relay k will be de-energized and release its armature k^1 from the contact e^1 , thus opening the shunt circuit and allowing the starting relay a to again pick up its armature a^1 . On the stop transmitter m becoming quiescent, the stop relay k will pick up its armature k^1 and again close therethrough the shunt circuit which will now be broken between the armature a^1 of the starting relay a and the contact e , and the apparatus will be re-set ready for the next signal.

With the stop relay k , I may, if desired, 15 combine the aforesaid manually-operated switch member g , which will be normally locked out of action by the locked depression of the stop key j , as shown, and will be arranged in parallel with the armature k^1 of the stop relay k . On releasing the switch member, the shunt circuit will be closed therethrough and a signal will be given continuously until the switch member g is operated by the stop key j to open the shunt 20 circuit. The arrangements described provide for either manual or automatic stoppage of the signal.

Separate sources of current may be employed for the starting relay circuit, the 30 local signaling circuit and the stop relay circuit, or, as shown, I may employ a common battery b , preferably arranged at the signaling station. In the latter case, there may be provided one or more variable resistances or rheostats n , which in addition to serving to adjust the sensitiveness of the transmitter c , as in my previous United States Patent No. 1,225,429, also serves or 35 serve to prevent the battery from short-circuiting through the shunt circuit when the local signaling circuit is closed.

For testing the working of the apparatus at the signaling station, I may provide in the circuit of the starting relay a a test key 45 o by the operation of which a switch member p in the relay circuit is actuated to disengage the contact h thereby opening the relay or line circuit to release the armature a^1 of the starting relay. I may also provide 50 a similar key for testing the operation of the relay k .

In some cases, I may arrange two or more starting transmitters in series with each other, as shown in Fig. 3, and also, if desired, two or more stop transmitters in series 55 with each other, the disturbance of either or any transmitter of each pair or set serving to de-energize the corresponding relay and effect the release of the armature thereof. 60 Such an arrangement of transmitters is especially applicable when the apparatus is used for giving warning at level crossings and to plate layers and others working on the track, when there may for example be 65 two starting transmitters in series with each

other and arranged one on the "up" track and the other on the "down" track at some distance from the crossing or place where the men are working. The terminal z (Fig. 3) is provided as a convenient means of connecting a conductor of each of two transmitters when these are employed in the manner described.

The armatures of the starting and stop relays may, when the relays are de-energized 75 by the disturbance of their respective transmitters, recede under the influence of springs, gravity, magnetic pull or the like.

I may employ any appropriate transmitter or current-reducing device operated by 80 mechanical vibrations. Preferably, I employ a device of the kind described in the specification of my said previous United States Patent No. 1,225,429. As illustrated in Figs. 4 and 5, such a device comprises two parallel reeds 34, 34^a so arranged and twisted as to produce between them a V-shaped gap which allows the reeds to vibrate independently of and in paths at right angles to each other, and a loose conductor or conductors 35 placed between flat carbon electrodes 36, 36^a carried by the reeds to conduct current from one electrode to the other. The reeds 34, 34^a are clamped at one end in a holder or support comprising two metal discs 37, 37^a which are secured to the box or casing 29 by a set screw 38 to grip the reeds between them. The reeds 34, 34^a are insulated from each other and from their 90 holder or support by mica or like insulating material 39 which will freely transmit to the reeds vibrations communicated to the casing and holder, the vibrational impulses supplied by a passing train being thus communicated to the reeds by way of their 100 nodes.

I may, however, employ a single reed carrying two electrodes suitably insulated from the reed and bridged by a loose conductor or conductors. As the loose conductors, I preferably employ hard carbon balls which are easily disturbed and which exercise but little damping effect upon the vibration of the reeds or reed. With the object of further reducing the damping, the 110 electrodes are preferably mounted on the reeds or reed between the nodal and free portions thereof. When two reeds are employed, the V-shaped gap may be obtained by twisting the reeds, as described in my 115 said previous specification, or the reeds may be flat and rest upon inclined seats, or the electrodes may themselves be shaped to give the required inclination, or appropriately-shaped pieces of insulating material may be 120 fitted between the reed and the electrodes to give the required inclination to the latter. A single reed may be twisted and/or bent to give the V-shaped gap between the electrodes, or the reed may be flat and an appro- 125 130

priately-shaped piece of insulating material may be fitted between the reed and the electrodes.

The loose carbon balls or other bridging medium may be retained in position by a muslin or other appropriate light cage carried by the reed or reeds or by the casing.

The starting relay, the test key, the local circuit and the signaling device therein, the shunt circuit, the stop relay and the manually operated switch member, the necessary batteries or a common battery, a terminal or terminals for connecting two or more transmitters in series, and a condenser for preventing sparking across the contacts of the relay or relays, comprising a complete receiver, may all be arranged in a single watertight box or casing. Conveniently, and as illustrated in Fig. 3, I may provide a box or casing *q* divided by a partition *q*¹ so as to form two chambers *r* and *t*. The chamber *r* is provided with a cover indicated at *r*¹ to constitute a watertight compartment for enclosing the starting and stopping relays *a*, *k*, the switch members *g*, *p* and contact *h* and a condenser *s*. The chamber *t* contains the necessary terminals for connecting up the transmitters, the battery, the bell, the resistance, and a terminal for connecting two starting transmitters in series. The terminal chamber *t* may be fitted with a hinged flap *t*¹ which can be thrown back to give access to the several terminals and to disclose the instructions for use which may be attached to the back of the flap.

With the arrangement illustrated the line circuit through the starting relay *a* is from battery *b* by lead *b*¹, terminal *u*, strip *v*, terminal *w*, lead *x*, transmitter *c*, lead *y*, terminal *z*, lead 2, transmitter *c*¹, lead 3, terminal 4, strip 5, lead 6, relay coil *a*, lead 7, switch member *p*, contact *h*, lead 8, strip 9, resistance or rheostat *n*, connecting binding screw 10 of strip 9 to binding screw 11 of strip 12, strip 12, terminal 13 and lead *b*² back to battery *b*. The line circuit through stop relay *k* is from battery *b* to strip *v* as before, lead 14, relay coil *k*, lead 15, strip 16, terminal 17, lead 18, stop transmitter *m*, lead 19, terminal 13 and lead *b*² back to battery *b*. When the starting relay *a* is de-energized to release its armature *a*¹ to close the bell and shunt circuits, the bell circuit is from battery *b* to strip *v*, lead 20, armature *a*¹, contact *e*, lead 21, strip 22, terminal 23, the bell *d*, terminal 24, strip 12, terminal 13 and back to the battery. Simultaneously the shunt circuit is completed from armature *a*¹ through contact *e*, lead 21, strip 22, lead *f*², armature *k*¹, contact *e*¹ and lead *f*¹, to contact *h* and thence back to the battery as before. If stop key *j* is released switch member *g* engages contact *h* and the shunt circuit is then completed from strip 22 to contact *h* by lead *f* and

switch member *g*. Leads 26, 26^a connect the condenser *s* across the strips 12, 22.

A strap or sling for convenience of transport may be attached to the transmitter or transmitters which may also be arranged in a watertight box or boxes. For temporarily clamping a transmitter to a railway sleeper, I provide a clamping screw permanently mounted on the box and furnished with a wing head or other convenient means of operation. Thus, as shown in Figs. 4 and 5, I may mount in holes in the cover 27 and the base 28 of the box 29, a wing headed screw 30 which has fitted to it after being passed through the hole in the cover, a collar 31, pin or other enlargement to prevent its being detached therefrom. The box 29 is preferably recessed at 32 so that the screw 30 does not pass through the interior thereof, in order to preserve watertightness. To obtain good mechanical contact between the transmitter and the sleeper, I provide the box with three feet 33 to form a tripod, and arrange the screw 30 as shown, so that it presses the feet with approximately equal force against the sleeper. The feet are formed with holes for securing screws when the transmitter is used in a permanent installation.

It will, of course, be understood that the invention is not limited to signaling in connection with railways or to the use of a bell as the local signaling medium.

What I claim as my invention, and desire to secure by Letters Patent is:

1. In a signaling system, a signal device, means including a relay and a circuit therefor having means for decreasing current therein without complete interruption for rendering said signal device active upon a decrease of current through the relay, means rendered effective simultaneously with the rendering effective of the signal device for shunting the relay and thereby incapacitating the relay against interrupting the action of the signal device, and means for rendering said last named means ineffective and thereby permit of the restoration of parts to normal position.

2. In a signaling system, a signal device, means including an armature for rendering said device active or inactive, means including a relay and a circuit therefor for controlling the armature to vary the activity of the signal device with a decrease in the current through the relay, means also controlled by the armature when it is in a position for rendering the signal device active for shunting said relay and thereby preventing further operation of the armature by further variations of the current in the circuit, and means for restoring the control of the said relay to the circuit comprising a relay mechanically separate and electrically connected to said first mentioned relay, and

- means for decreasing the current in said second relay.
3. In a signaling system, a signal device, means including a relay, a circuit therefor, and a current varying device in said circuit for rendering the signal device active upon a variation of current through the relay by the current varying device, means including a second circuit controlled by the relay and automatically closed thereby when said signal device is rendered active for preventing interruption of the operation of the signal device by the relay during further current variations in the first mentioned circuit, and means for opening said second mentioned circuit to restore the control of the signal device to the relay comprising a second relay, and means for decreasing the current therethrough without complete interruption thereof.
4. In a signaling system, a signal device, means including a relay, a circuit therefor, and a current varying device in said circuit for rendering the signal device active upon a variation of current through the relay by the current varying device, means including a second circuit controlled by the relay and automatically closed thereby when said signal device is rendered active for preventing interruption of the operation of the signal device by the relay during further current variations in the first mentioned circuit, a circuit controller, means comprising circuits and a loose contact adapted to produce a decrease in current in said circuit controller and means including an electromagnetic device controlled by said circuit controller for opening said second mentioned circuit to restore the control of the said signal device to the relay.
5. In a signaling system, a signal device, means including a relay, a circuit therefor, and a current varying device in said circuit for rendering the signal device active upon a variation of current through the relay by the current varying device, means including a second circuit controlled by the relay and automatically closed thereby when said signal device is rendered active for preventing interruption of the operation of the signal device by the relay during further current variations in the first mentioned circuit, a circuit controller, and means including a manually operated switch and an electromagnetically controlled switch independently operative to restore said signal device to the control of the relay whenever either of said switches is operated, said electromagnetically controlled switch being in turn controlled by the circuit controller.
6. In a signaling system, a signal device, a source of current, a relay, an armature biased for movement to one position and held by said relay in another position, a current varying device, a normally closed circuit including a source of current, the relay and the current varying device, means including a circuit for controlling the signal device connected to the source of current and controlled by the armature so as to be closed thereby when said armature is released by the relay upon a decrease in current therein for rendering the signal device effective, means including a third circuit shunted across the relay and closed by the armature simultaneously with the closing of the signal device controlling circuit for preventing operation of the armature by the relay, and a vibration responsive means, an auxiliary relay, and circuits cooperating with said first mentioned relay for returning said armature to its unreleased position.
7. In a signaling system, a signal device, a source of current, a relay, an armature biased for movement to one position and held by said relay in another position, a current varying device, a normally closed circuit including the source of current, the relay and the current varying device, means including a circuit for controlling the signal device connected to the source of current and controlled by the armature so as to be closed thereby when said armature is released by the relay when the current therein is decreased, for rendering the signal device effective, means including a third circuit shunted across the relay and closed by the armature simultaneously with the closing of the signal device controlling circuit for preventing operation of the armature by the relay, and means for opening the third circuit to restore the control of the signal device to said relay comprising a vibration responsive means and an auxiliary relay.
8. In a signaling system, a signal device, a source of current, a relay, an armature biased for movement to one position and held by said relay in another position, a current varying device, a normally closed circuit including the source of current, the relay and the current varying device, means including a circuit for controlling the signal device connected to the source of current and controlled by the armature so as to be closed thereby when said armature is released by the relay when the current therein is decreased, for rendering the signal device effective, means including a third circuit shunted across the relay and closed by the armature simultaneously with the closing of the signal device controlling circuit for preventing operation of the armature by the relay, a second current varying device, and electromagnetic means controlled by the second current varying means for opening the third circuit to restore the control of the signal device to said relay comprising a vibration responsive means and an auxiliary relay.
9. In a signaling system, a signal device,

- means including a relay, a circuit therefor, and a current varying device in said circuit for rendering the signal device active upon a variation of current through the relay by 5 the current varying device, means including a second circuit controlled by the relay and automatically closed thereby when said signal device is rendered active for preventing interruption of the operation of the signal device by the relay during further current variations in the first mentioned circuit, means for opening said second mentioned circuit to restore the control of the signal device to the relay, a test key in the relay 10 circuit for varying the current therein to cause an operation of the signal device and means comprising a vibration responsive device and an auxiliary relay mechanically separate and electrically connected to said 15 first mentioned relay for interrupting the operation of said signal device by return of said relay to unactuated position.
10. In a signaling system, a signal device, a relay having an armature and contacts, a 20 source of electrical energy, connections between said source of current, said signal device and the contacts of said relay whereby said signal device is actuated upon the closure of said contacts, and vibration responsive means adapted to the production of a 25 decrease in current therethrough without complete interruption thereof, connected in circuit with said relay and said source of electrical energy for the actuation of the 30 contacts of said relay, an auxiliary circuit 35 cooperating with said relay in shunt thereto, whereby the contacts of said relay are held in position for operation of said signal device after actuation by said vibration responsive means, and a plurality of means 40 for restoring said relay contacts to unactuated position, one thereof comprising a manually operable switch, another thereof comprising a second relay device mechanically 45 separate from said first mentioned relay and connected in said auxiliary circuit, and a second vibration responsive means 50 cooperating therewith for the actuation thereof whereby said first mentioned relay is restored to unactuated position.
11. In a signaling system, a signal device, and means for the sustained operation thereof in response to the occurrence of vibrations, comprising a vibration responsive 55 means adapted to produce a change in an electric current having a value less than the normal steady current, a relay connected thereto having contacts cooperating with
- said signal device and adapted to be actuated by a change in current therein, a 60 source of electrical energy cooperating therewith, means comprising an auxiliary circuit for holding said relay in the actuated position after the discontinuance of vibrations, and means for restoring said relay 65 by removal of the effect of said auxiliary circuit comprising a second vibration responsive means, a second relay cooperating therewith and connections therefrom to said auxiliary circuit. 70
12. In a signaling system, a signal device, a plurality of vibration responsive means adapted to the production of a partial change in the value of an electric current, a relay having contacts, said contacts cooperating with said signal device, said relay 75 cooperating with said vibration responsive means, whereby a change in current actuates said signal device, an auxiliary circuit for holding said contacts in the actuated 80 position, and means for removing the holding effect of said auxiliary circuit, comprising a further plurality of vibration responsive means and an auxiliary relay cooperating therewith and with said auxiliary circuit, whereby actuation of any of said 85 second mentioned vibration responsive means restores said first mentioned relay to unactuated position and interrupts the operation of said signal. 90
13. In a signaling system, a signal device, a plurality of vibration responsive means adapted to the production of a partial change in the value of an electric current, a relay having contacts, said contacts cooperating with said signal device, said relay 95 cooperating with said vibration responsive means, whereby a change in current actuates said signal device, an auxiliary circuit for holding said contacts in the actuated position, means for removing the holding effect of said auxiliary circuit, comprising a further plurality of vibration responsive means and an auxiliary relay cooperating therewith and with said auxiliary circuit, whereby actuation of any of said second mentioned vibration responsive means restores said first mentioned relay to unactuated position and interrupts the operation of said signal, and manual means also cooperating 100 with said auxiliary circuit for the interruption of the effect thereof. 105
- In witness whereof I have hereunto set my hand.

JOHN GARDNER.
